UNITED STATES PATENT OFFICE.

THOMAS ALFRED CHRISTIAN, OF MERCED FALLS, CALIFORNIA, ASSIGNOR OF ONE-THIRD TO FRED. A. STEWART AND ONE-THIRD TO LEMUEL F. LONG, BOTH OF MERCED FALLS, CALIFORNIA.

SPIKE-PULLER.

1,285,561.

Specification of Letters Patent. Patented Nov. 19, 1918.

Application filed May 20, 1918. Serial No. 235,540.

To all whom it may concern:

Be it known that I, THOMAS A. CHRISTIAN, a citizen of the United States, residing at Merced Falls, in the county of Merced and State of California, have invented certain new and useful Improvements in Spike-Pullers, of which the following is a specification, reference being had to the accompanying drawings.

10 This invention relates to devices for withdrawing spikes and particularly to a device designed for the purpose of withdrawing railroad spikes from ties.

Generally speaking, the object of my invention is to provide a spike pulling device having a clamp whereby it may be readily engaged with the head of a rail and having a lever and spike engaging jaws mounted upon the lever.

20 A further object of the invention is to provide a device of this character in which the spike engaging member is provided with opposed jaws which are automatically forced inward around the head of the spike

25 as the spike engaging member is lowered against the base of the rail and which jaws, at a predetermined point, are automatically locked against opening movement to permit the application of power to the lever to 30 withdraw the spike.

Other objects will appear in the course of the following description.

My invention is illustrated in the accompanying drawings, wherein:

35 Figure 1 is a sectional view of a rail and a portion of a tie, the spike puller being in elevation;

Fig. 2 is a front elevation of the lever support and lever;

40 Fig. 3 is a front elevation of the spike engaging member;

Fig. 4 is an elevation of the bolt 16;

45 Figs. 5 and 6 are vertical sectional views of the spike engaging member, the gripping jaws being in elevation;

Fig. 7 is a sectional view on the line 7-7 of Fig. 5; and

50 Fig. 8 is a side elevation of the spike puller with a different arrangement of the parts from that shown in Fig. 1.

Referring to these figures, it will be seen

that my device comprises a saddle 10 or base which is adapted to rest upon the head of a rail A as in Fig. 1, and which has two laterally disposed depending flanges 11 embracing the head of the rail, each of these flanges being cut away as at 12, the cut-away portion of one flange being disposed diagonally opposite to the cut-away portion of another flange.

Extending upward from this base or saddle 10 is a standard 13 which is bifurcated at its upper end as at 14 to provide laterally spaced ears, one of these ears being formed with a square opening 15 and the other with a circular opening. Pivoted upon a pivot pin 16 extending through the openings in the ears is a lever 17. The pivot pin 16 is preferably squared at one end to engage with the squared opening 15 so as to prevent a rotation of the pivot pin, the lever rotating upon the pivot pin and means are preferably provided for detachably engaging the pivot pin 16 to prevent its accidental withdrawal.

75 Pivoted upon the standard 13 on each side face thereof, immediately above the base 10, are the locking hooks 18, these hooks being pivoted upon a transversely extending pivot pin 19, which passes through the standard. Each hook is disposed in alignment with a cut-away portion 12. The hooks are so formed that when they are forced inward they will engage beneath the head of the rail.

80 Pendant from the bifurcated end 20 of the lever 17 is a hollow body 21 constituting a jaw carrier and having an upwardly extending stem 22 which is disposed in the bifurcated end of the handle and pivoted thereto by a pivot pin 23. The body 21 is hollow and the lower edges of its side walls extend downward and inward from the side edges of the head, as at 24, and then upward and inward as at 25. Disposed within this body 21 are the shanks 26 of opposed jaws 27. The shanks are narrower than the jaws thereby leaving upwardly inclined shoulders 28 which engage with the upwardly inclined edges 25 of the side walls of the body 21. The inner faces of the jaws are formed to provide downwardly and inwardly ex-

tending bolt engaging faces 29 on each jaw. The jaws are urged outward by means of a spring 30 disposed between the shanks 26 and held in suitable sockets in the shanks.

- 5 Each of the shanks 26 is provided with a pin 31 which extends out through a vertically extending slot 32 formed in the corresponding end wall of the body 21, this slot being about twice as long as the diameter of 10 the pin 31. Thus the jaws and their shanks may have a limited longitudinal movement with reference to the body 21. Just above the pins 31 the shanks 26 are formed with inwardly extending shoulders 33. The side 15 walls of the body 21 are formed with square openings 34, and operating through these openings is a locking plunger 35 having a stem 36 which extends out through a U-shaped yoke 37, the plunger being urged inward by means of a coiled compression spring 38 and the spindle 36 being provided with a handle 39. When the locking plunger 35 is fully retracted, and the jaws 27 20 with their shanks 36 are lowered to the full extent permitted by the slots 32, the locking plunger will bear against the side faces of the shoulder 33. When, however, the jaws 27 have been forced upward to the full extent of the slots 32, the shoulders 33 are carried upward sufficiently to permit the locking 25 plunger to be projected beneath the shoulders, thereby locking the shanks of the jaws 27 from downward movement. While I do not wish to limit myself to this, I preferably provide a double coiled spring 40 which is mounted upon the pivot bolt 19 and which bears against the under side of the lever urging the handle of the lever upward.

40 In the practical use of this invention, the saddle 10 is clamped upon the head of a rail by means of the clips or hooks 18 and in this position is firmly supported upon the rail. The lever 17 is then raised so that the jaw carrier 21 is shifted downward toward the spike to be withdrawn. The jaws 27 at 45 this time are spread apart to their greatest extent but are lowered so that the pins 31 are disposed at the lower ends of the slots 32. In this position the biting edges of the jaws 50 27 are spaced apart a distance greater than the head of the spike to be withdrawn. Now as the lever 17 is raised and the jaws are forced downward against the tie, the shoulders 28 will be forced upward in engagement with the inclined faces 24 and as the carrier 21 is forced downward, the upward pressure on the jaws 27 will cause the shoulders 28 to travel against the inclined faces 25 and travel toward each other so 55 that eventually the jaws will close beneath the head of the spike. When the jaws have been forced inward and, therefore, upward a predetermined degree, the shoulders 33 will have passed the locking plunger and the

plunger will spring inward locking the jaws 65 from downward and consequently locking them from outward movement. At this point the jaws are firmly engaged with the head of the spike and cannot be moved outward. Then the outer end of the lever is 70 depressed to withdraw the spike. This may be accomplished by exerting a continuously acting downward force upon the outer end of the lever or by striking the outer end of the lever as with a sledge hammer and the spike 75 will be withdrawn. When the spike is fully withdrawn the plunger 35 is retracted by pulling on the handle 39 and as soon as it has been fully retracted the spring 30 will cause the jaws to spring apart and to drop 80 downward to the extent permitted by the slots 32, thus releasing the spike. The device is then ready for the withdrawal of another spike. It will be obvious that the saddle or support 10 may be shifted along 85 the rail to new positions without detaching it from the rail so that a plurality of spikes may be withdrawn very quickly. It is to be noted that the upwardly extending stem 22 of the head or body 21 is relatively large 90 in cross section to receive the impact of a sledge hammer which may be used for the purpose of forcing the member 21 downward and thereby forcing, as before described, the jaws 27 toward each other into 95 engagement with the spike.

The device above described is very simple and strong, is very convenient, has few parts and is thoroughly effective in action. While I have illustrated certain details of construction which I have used in practice, yet it is to be understood that the principle of the invention might be embodied in other forms, without departing from the spirit of the invention as defined in the appended 105 claims.

In Fig. 8 I have shown how my spike puller may be used where the spike to be pulled is disposed at a lower elevation than the support as, for instance, the rail A upon which the lever is mounted. In this case, the body 21 is pivoted to a shackle a in turn connected to a link b which is engaged by the pin 23. It will be obvious that with either the construction shown in Fig. 1 or that shown in Fig. 8, the member 21 may be forced down toward the spike to be engaged by the gripping jaws by means of a sledge hammer and where the jaws are engaged with the spike, the lever 17 may be engaged 110 with the member 21 or the shackle a and link b may be engaged with the lever and member 21.

By providing a spike engaging member which may be hammered down to force the 115 gripping jaws inward into engagement with the spike it is easy to apply the member to spikes which have even been driven quite 120

125

deeply into the wood of the tie and secure a firm hold on the spike.

Having described my invention, what I claim is:

5. 1. A spike puller comprising a supporting base, a lifting member mounted upon the base, a jaw carrier operatively connected to the lifting member, jaws operatively mounted on the jaw carrier, means for forcing said jaws inward upon a downward movement of the jaw carrier relative to the jaws, and means for locking the jaws from movement away from each other after the jaws are moved inward a predetermined distance.
10. 2. A spike puller comprising a supporting base, a lifting member mounted on the base, a jaw carrier depending from one end of the member, opposed spike gripping jaws mounted in the carrier and extending below the carrier, the jaws having a limited vertical movement within the carrier and being movable toward or from each other, means for automatically shifting the jaws toward each other as the jaws move upward in the carrier, and means for locking the jaws from movement away from each other after the jaws are moved inward a predetermined distance.
15. 3. A spike puller comprising a supporting base, a lifting member mounted on the supporting base, a jaw carrier pivoted to and depending from one end of the member, the jaw carrier being hollow and open at its lower end, a pair of confronting jaws disposed at the lower end of the carrier and having shanks extending up thereinto, the jaws and shanks being movable toward or from each other and having a limited vertical movement within the carrier, the carrier being formed with upwardly and inwardly inclined faces and the jaws having shoulders engaging with said faces whereby, as the jaws are forced downward against a tie, they will be forced toward each other by contact of the shoulders with said faces, and means for locking the jaws against outward movement after they have moved toward each other a predetermined distance.
20. 4. A spike puller comprising a supporting base, a lifting member mounted on the supporting base, a jaw carrier pivoted to and depending from one end of the member, the jaw carrier being hollow and open at its lower end, a pair of confronting jaws disposed at the lower end of the carrier and having shanks extending up thereinto, the jaws and shanks being movable toward or from each other and having a limited vertical movement within the carrier, the carrier being formed with upwardly and inwardly inclined faces and the jaws having shoulders engaging with said faces whereby as the jaws are forced downward against a tie they will be forced toward each other by contact of the shoulders with said faces, means for locking the jaws against outward movement after they have moved toward each other a predetermined distance, said means comprising a locking plunger mounted upon the carrier, and shoulders formed upon the shanks of the jaws beneath which said plunger engages.
25. 5. A spike puller including a supporting member, a lever pivoted thereto, a jaw carrier pivoted to one end of the lever and depending therefrom, the carrier having a hollow body open at its lower end, the side walls of the lower end of the carrier having their lower edges upwardly and convergently inclined, jaws disposed below the lower end of the carrier and having inclined shoulders engaging the said inclined faces and having shanks extending upward into the carrier, a pin projecting from each shank into the end wall of the carrier, the end wall of the carrier having a vertical slot for the pin, a spring engaging the shanks and urging them apart, a plunger mounted upon one side wall of the carrier and urged into the carrier, the shanks of the jaws being provided with shoulders beneath which said pin engages when the shanks are raised and the jaws are forced toward each other to thereby lock the jaws from outward movement.
30. 6. A spike puller comprising a base, a lever pivotally mounted upon the base, a jaw carrier having a hollow body open at its lower end and having an upwardly extending relatively thick stem pivoted to the lever and adapted to receive the impact of a hammer, the lower edges of the side wall of the carrier being upwardly and centrally inclined, jaws disposed below the side walls of the carrier and having shanks extending into the carrier, the jaws having shoulders engaging with the inclined lower edges of the carrier walls, means supporting the jaws and shanks for limited vertical movement within the carrier and for movement toward or from each other, a spring urging the jaws away from each other, and means for automatically locking the jaws from downward movement when the jaws have been forced upward and toward each other.
35. 7. A railway spike puller comprising a saddle adapted to fit over the head of a rail, freely swinging hooks mounted upon the saddle and adapted to be shifted beneath the head of the rail to lock the saddle thereto, the saddle having an upwardly extended bifurcated standard, a lever pivoted in said bifurcation of the standard, and spike engaging jaws operatively pivoted to the lever.
40. 8. A railway spike puller comprising a saddle adapted to rest upon a rail, an upwardly extending standard mounted on the saddle, a lever pivoted to the upper end of

the standard, a jaw carrier pivoted to the lever, jaws mounted upon the carrier, means for forcing the jaws toward each other to grip a spike when the carrier is forced downward, and means on the saddle for holding the saddle to the rail against upward movement when the carrier is forced downward.

In testimony whereof I hereunto affix my signature in the presence of two witnesses:

THOMAS ALFRED CHRISTIAN.
